THERMOSTAT

Norbert Thomas Wolfe, Minnetonka, Minn., assignor to Honeywell Inc., Minneapolis, Minn.

Filed Feb. 12, 1971, Ser. No. 115,150

Term of patent 14 years

Int. Cl. D10—04

U.S. Cl. D52—7 R

FIG. 1

FIG. 4

FIG. 2

FIG. 3

FIG. 1 is a top plan view of a thermostat showing my new design, the bottom plan view being a mirror image thereof;

FIG. 2 is a front elevation view thereof;

FIG. 3 is a side elevation view thereof, the opposite side view being substantially a mirror image, thereof; and

FIG. 4 is a fragmentary cross-sectional view of FIG. 1 taken along line 4-4.

I claim:

The ornamental design for a thermostat, as shown and described.
